CLAIM

The ornamental design for an electroluminescent wall plate, as shown and described.

DESCRIPTION

FIG. 1 is a front elevational view of an electroluminescent wall plate showing my design, with the stippling showing contrasting surface appearance, particularly, a luminescent surface appearance when energized electrically;

FIG. 2 is a rear elevational view thereof;

FIG. 3 is a right side elevational view thereof;

FIG. 4 is a left elevational view thereof; and,

FIG. 5 is a top plan view thereof with the bottom plan view being a mirror image thereof.
